VIAL CLOSURE

Floyd A. Terwilliger, 1264 Culver Road,
Rochester, N.Y.

Filed Mar. 31, 1960, Ser. No. 59,968

Term of patent 14 years

(Cl. D58—26)

FIG. 1.

FIG. 2.

FIG. 3.

FIG. 4.

FIG. 5.

FIG. 1 is a side elevation of a vial closure embodying my new design;

FIG. 2 is a top plan view thereof;

FIG. 3 is a bottom view thereof;

FIG. 4 is a transverse section therethrough taken on the line 4—4 of FIG. 1, looking in the direction of the arrows; and

FIG. 5 is an axial section through the closure taken on the line 5—5 of FIG. 1, looking in the direction of the arrows.

I claim:

The ornamental design for a vial closure, substantially as shown.
